UNITED STATES PATENT OFFICE.

HENRY C. SIMMONS, OF ATLANTA, GEORGIA.

WRITING-PAD.

1,345,558.

Specification of Letters Patent.

Patented July 6, 1920.

Application filed February 21, 1920. Serial No. 360,361.

To all whom it may concern:

Be it known that I, HENRY C. SIMMONS, citizen of the United States, residing at Atlanta, in the county of Fulton and State of Georgia, have invented certain new and useful Improvements in Writing-Pads; and I do hereby declare the following to be a full, clear, and exact description of the invention, such as will enable others skilled in the art 10 to which it appertains to make and use the same.

This invention relates to table writing pads and more particularly to that type of writing pads adapted to be used on desks or 15 tables and in which the writing paper is drawn as needed from a roll.

The object of this invention is to provide a simple inexpensive and easily manufactured writing pad of the type indicated 20 from one piece of sheet metal embracing various novel arrangements and combinations of parts as hereinafter more particularly specified.

One sheet of drawings accompanies this 25 application as part thereof, in which like reference characters denote like parts throughout.

Referring to the drawings:

Figure 1 represents a sheet of metal as 30 preliminarily die stamped.

Fig. 2 represents a plan of the device after the second step in its manufacture and in its completed form.

Fig. 3 is a side elevation from Fig. 2.

Fig. 4 represents a side elevation of the 35 device as in use with roll of paper in position for use.

From a suitable piece of sheet metal, such as brass having sufficient rigidity and a certain degree of spring resilience, a blank is 40 cut having a body part A of rectangular or other desirable form, lateral wings, B—B, parallel slots D—D and C and notched edge

1. In the same operation knobs C—C may 45 be punched upwardly in the wings B—B, and the parts of the body F located between the slots D—D and between slot C and the notched edge H may also be stamped upwardly until the lower faces of part F and 50 G are raised above the plane of the top surface of the body A about the thickness of a sheet of paper. The wings B—B are then bent upwardly until they are parallel to each

other and perpendicular to the body A with the knobs C—C projecting inwardly and 55 opposite to each other.

In operation a roll of paper such as is widely marketed for adding machines, and which is wound on a shallow spool, is sprung into position between the wings 60 B—B the knobs C—C centering in the bore, of the spool and holding same resiliently so that the spool is rotatable but will not turn of itself. The free edge of the paper is then passed through the slots D—D under 65 the raised part F over the body A which serves as a hard writing surface through the slot E and out under the raised part G past the notched edge H. As used, the paper is drawn out farther and readily torn off on 70 the notched edge H.

Having just fully described my invention I claim:

1. A writing pad holder comprising a body having lateral wings, knobs depressed 75 from said wings and guides formed in said body and limited therefrom by parallel slots cut therein.

2. A writing pad holder constructed from one piece of suitable sheet metal having in 80 combination a flat body provided with parallel slots, parts of said body limited by said slots being raised above the plane of said body and wings integral with said body having knobs stamped therein, said knobs 85 situated opposite each other, and adapted to center and resiliently hold a roll of writing paper.

3. A writing pad holder constructed of one sheet of suitable sheet metal comprising 90 a body provided with parallel slots, guides formed from said body and limited by said slots, a toothed edge on one of said guides and spaced supports bent from said body and provided with oppositely disposed inwardly directed knobs adapted to center and 95 resiliently hold a roll of paper.

4. A writing pad holder comprising a body having lateral wings, knobs depressed inwardly from said wings and guides 100 formed in said body and limited therefrom by parallel slots cut therein.

5. A writing pad holder constructed from one piece of suitable sheet metal, having in combination a flat body provided 105 with parallel slots, parts of said body being

limited by said slots by being raised above the plane of said body and wings integral with the body, having inwardly directed knobs stamped therein, said knobs being situated opposite each other and adapted to center and resiliently hold a roll of writing paper.

In testimony whereof I affix my signature in presence of two witnesses.

HENRY C. SIMMONS.
